UNITED STATES PATENT OFFICE.

RAYMOND K. SINER, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

HEADBAND.

Application filed June 8, 1925. Serial No. 35,627.

My invention relates to certain improvements in head bands, or bandeaux, for keeping the hair in place.

The object of the invention is to simplify the construction of a head band, or bandeaux, which is made from a strip of elastic ribbon.

In the accompanying drawings:

Fig. 1 is a face view of the improved head band;

Fig. 2 is a rear view;

Fig. 3 is a view of the blank from which the head band is made; and

Figs. 4, 5, 6 and 7 are views showing the different steps in the manufacture of the head band.

Referring to the drawings, 1 is a strip of elastic fabric, which is cut to the proper length. The strip is then folded longitudinally, as shown in Fig. 4, and is cut on the diagonal line 2 so that, when the strip is opened, as in Fig. 5, it has a V-shaped incision at each end.

When the fabric is folded, as in Fig. 4, the diagonal edges are secured together by over seam stitches 3, as in Fig. 6, and, when

the fabric is opened, as in Fig. 7, the ends 4 of the head band are curved and terminate in a point 5.

Snap fastenings 6 and 7 are attached to the head band. The fastening 6 is secured 30 on the outer face of the band, as in Fig. 1, and the snap 7 is secured to the opposite face of the band, as illustrated in Fig. 2, so that—when the band is worn—the ends are secured together by the two snaps. 35

By constructing a head band in the manner hereinbefore described, there is a single 40 ply of fabric throughout the entire length of the band, which gives it a neat appearance. 40

I claim:

As a new article of manufacture, a head band made of elastic fabric, having a V-shaped incision at each end, the two edges opening at the incision being stitched together so as to form a single ply; a fastening device at each end of the band for securing the ends together when said band is used. 45
